UNITED STATES PATENT OFFICE.

WILLIS P. THOMAS, OF DETROIT, MICHIGAN, ASSIGNOR, BY MESNE ASSIGNMENTS, TO DIAMOND POWER SPECIALTY CORPORATION, OF DETROIT, MICHIGAN, A CORPORATION OF MICHIGAN.

BOILER CLEANER.

Application filed June 6, 1919. Serial No. 302,296.

The invention relates to boiler cleaners and has particular reference to a construction in which the movement of the blower jets in relation to the surface to be cleaned is effected by the pressure of the steam or other blowing medium discharged from the jets. To this end the invention consists in the construction as hereinafter set forth.

In the drawings:

10 Figure 1 is an elevation showing the blower as applied to a boiler;

Figure 2 is a longitudinal section through the motor and steam supply connection;

Figure 3 is an end elevation.

15 My improved construction is applicable to various types of boilers but is specifically shown as applied within smoke-boxes of adjacent boilers of a battery.

A and A' are the adjacent boilers having 20 the smoke boxes B and B', with which the flues passing through the boilers are connected. C is a steam conduit or header which extends across the space between the smoke-boxes and into the same, passing 25 through the several compartments of each box and being provided with suitable laterally-extending blower tubes D. E is a cylinder arranged centrally of the space between the boilers, and F is a piston within 30 the cylinder E which is mechanically connected to the oppositely extending sections of the header C. The piston divides the cylinder into two chambers which are respectively in communication with the sections of the header. In the specific construction shown the piston is hollow and has 35 a central division wall F' which separates the space into two chambers respectively communicating through ports F² with the 40 chambers of the cylinder. Each end of the piston is provided with a threaded socket F³ and the headers are correspondingly threaded and engaged with said sockets.

The steam or blowing medium is applied 45 to the cylinder E alternately at opposite ends thereof. G is the supply conduit and H and H' are branch conduits connected therewith and leading to the opposite ends of the cylinder. I is a three-way valve located at the junction between the conduits G, H and H' and the arrangement is such 50 that by adjusting said valve the steam may

be passed alternatively to the two branches.

With the construction as thus far described it will be evident that when steam is admitted to one end of the cylinder E, it will pass into the chamber within the piston and into the header C which is connected thereto. At the same time, the pressure acting against the piston will force the same to the opposite end of the cylinder. Thus, while the steam is being discharged from the tubes D, said tubes will be moved across the ends of the flues and will successively clean the same. When the piston has completed its travel, by reversing the valve 1 steam will be cut off from the first end of the cylinder and will be admitted to the opposite end thereof. This will cause a discharge of steam through the opposite section of the header and will also cause the reverse movement of the piston so that the header and the jet tubes connected thereto will be moved across the ends of the flues. This operation may be repeated as long as necessary in order to effect a thorough cleaning of the flues. It is, however, desirable to retard the movement of the piston so as to permit the jets to remain for a short interval in registration with each of the successive flues. This I have provided for by forming, preferably 75 integral with the cylinder E, a parallel cylinder J in which is placed a piston K connected by the piston rod L with an arm M clamped, or otherwise secured, to one section of the header. The opposite ends of the cylinder J are connected with the opposite ends of a by-pass conduit N and a valve O in this conduit may be adjusted to variably restrict the same. The cylinder J is filled with oil or other liquid and will therefore operate as a retarding device for the piston F. By adjusting the valve O the speed of movement may be regulated to that which is best suited for the cleaning opera- 85 90 95

What I claim as my invention is:

1. In a boiler cleaner, the combination with a pair of blowers, of oppositely-extending headers for said blowers movable to shift 100 said blowers transversely to the direction of their discharge and connected to each other, and a stationary header with which said movable headers are telescopically engaged,

- permitting the reciprocation thereof while maintaining the supply of the blowing medium.
2. In a boiler cleaner, the combination with a pair of blowers, of aligned headers for said blowers movable to shift said blowers transversely to the direction of their discharge and connected to each other, a stationary header with which said movable headers are telescopically engaged, and a piston connected with said movable headers and actuated by the pressure of the blowing medium to reciprocate said headers.
3. In a boiler cleaner, the combination with a pair of boilers and smoke boxes therefor, of blowers arranged in said smoke boxes and movable in a plane transverse to the direction of discharge, aligned headers extending out from said smoke boxes and connected to each other, a stationary header in the space between said smoke boxes with which said movable headers are telescopically engaged, and means operated by the pressure of the blowing medium within said stationary header for reciprocating said movable headers.
4. In a boiler cleaner, the combination of a cylinder, a piston therein, aligned headers mechanically connected with said piston and in communication with the chambers upon opposite sides thereof, and means for supplying the blowing medium to said cylinder alternately upon opposite sides of said piston.
5. In a boiler cleaner, the combination of a cylinder, a piston therein, headers connected to said piston and passing out through opposite ends of said cylinder, said headers being in communication respectively with the chambers on opposite sides of said piston, means for supplying the blowing medium to said cylinder alternately upon opposite sides of said piston, and means for retarding movement of said piston under the pressure of said blowing medium.
6. In a boiler cleaner, the combination of a cylinder, a piston therein, a pair of aligned headers connected to said piston and extending out from the opposite ends of said cylinder, said headers being respectively in communication with the chambers on opposite sides of said piston, means for supplying the blowing medium to said cylinder alternately on opposite sides of said piston, a cylinder arranged parallel to said first-mentioned cylinder, a piston therein, a connection between said piston and one of said headers, a by-pass establishing communication between the opposite ends of the last-mentioned cylinder, and means for variably restricting said by-pass.
7. In a boiler cleaner system, the combination with a plurality of boilers to be cleaned, of a plurality of reciprocating headers for cleaning said boilers, and a single cylinder mechanism arranged between said boilers and operatively connected to said headers for actuating said headers simultaneously.
8. In a boiler cleaner, the combination with a reciprocatory blower header, of a cylinder into which said header is extended, and a piston in said cylinder for actuating said header, said piston having a fluid inlet for the header, said inlet opening into the cylinder at the side of the piston from which said header projects.
9. In a boiler cleaner, the combination with a movable blower element adapted to discharge a cleaning fluid during its movement for cleaning parts of a boiler, of means for regulably retarding the movement of said blower element for obtaining a predetermined velocity of travel of the blower element whereby an accurate predetermination of the period of cleaning fluid discharge upon a given surface of the boiler is obtained.
- In testimony whereof I affix my signature.

WILLIS P. THOMAS.
